ADJUSTABLE STERILIZING CASE

Isaiah D. Durham, Columbia, S. C.

Application March 20, 1935, Serial No. 12,076

4 Claims. (Cl. 99—18)

This invention relates to an adjustable sterilizing case for hypodermic syringes, the general object of the invention being to make the case adjustable for different sizes of syringes and to make the case compact so that it can be readily carried in a physician's satchel, for instance, and which will thoroughly sterilize all the parts of the syringes so that they will be ready for immediate use.

10 This invention also consists in certain other features of construction and in the combination and arrangement of several parts, to be herein-after fully described, illustrated in the accompanying drawing and specifically pointed out in the appended claims.

15 In describing the invention in detail, reference will be had to the accompanying drawing wherein like characters denote like or corresponding parts throughout the several views, and in which:

20 Figure 1 is an elevation of the case.

Figure 2 is a longitudinal sectional view through the case.

25 Figure 3 is a section on the line 3—3 of Figure 2.

Figure 4 is a top plan view of the container with the disk removed.

Figure 5 is a transverse sectional view through the cap.

30 In this drawing the numeral 1 indicates the body part of the case which is exteriorly threaded from the top to a point adjacent the bottom, as shown at 2. The side walls of the case are of considerable thickness and the bottom of the case has a chamber 3 therein, at the top of which the thickened portion of the sides terminate. Vertical passages 4 extend from the chamber through the thickened parts 2 to the upper end of the body and the interior of the walls are threaded

35 from top to bottom as shown at 5. An elongated cap 6 is internally threaded to engage the external threads 2 of the body and by making the skirt of this cap of considerable length the top of the cap has a wide range of adjustments toward

40 and away from the upper end of the body. A ring 7 carrying a gasket 8 is threaded internally to engage the threads 2 and after the cap has been adjusted to the desired position the ring 7 is threaded upwardly on the body to press the

45 gasket against the lower end of the cap to insure a fluid-tight joint and thus prevent leakage of the fluid placed in the body. A cylindrical container 9 provided with exterior threads 10 is adapted to be threaded in the body and said container has a bottom part 11 which is provided with

5 a pair of oppositely arranged large holes 12 and a pair of smaller holes 13 as shown in Figure 5. The upper end of the container is also closed as shown at 14 and this top has a pair of oppositely arranged holes 15 substantially the same size as the holes 12 in alignment with said holes 12. A tubular member 16 depends from the central part of the top part 14 and is provided with perforations 17 so that the solution entering the member 9 through the holes 13 from the body can enter the tubular member. This member has a threaded part 18 projecting above the top part 14, the threaded portion of which is adapted to receive a cap 19. This cap not only acts to close the upper end of the tubular part 16 but it also 10 rotatably holds in place a disk 20 which has a pair of oppositely arranged holes 21 therein and a pair of oppositely arranged small holes 22 therein. The large holes 21 are adapted to receive syringes A of large diameter. When these 15 syringes are to be placed in the device the disk is turned to place the large holes 21 over the large holes 15 and 12 so that the syringes pass through the three sets of holes as shown in Figure 2. When small syringes are to be used the 20 disk is turned to place the small holes 22 over the large holes 15 and then the small syringes can be passed through the holes 22 and through the holes 15. As it will be seen when the holes 21 25 are in register with the holes 15 the holes 22 are 30 closed by the top part 17 of the container and when the small holes 22 are over the holes 15 the large holes will be closed.

As it will be seen both the cap and the container 9 can be adjusted to a desired position 35 relative to the body and when the parts are in the position shown in Figure 2 sterilizing solution in the body can pass through the passages 4 into the cap and thus contact the upper portions of the syringes while the solution entering 40 the container 9 through the holes 13 will contact other portions of the syringes. The tubular member 16 is designed to receive the needle or needles of the syringes and the solution entering the holes 17 will contact the needle.

45 It is thought from the foregoing description that the advantages and novel features of the invention will be readily apparent.

It is to be understood that changes may be made in the construction and in the combination 50 and arrangement of the several parts, provided that such changes fall within the scope of the appended claims.

What is claimed is:—

1. A device of the class described comprising 55

- a body internally and externally threaded, the body being of cylindrical shape with its lower end closed, a cap having a skirt internally threaded for engaging the external threads of the body, 5 whereby the cap can be adjusted on the body, a container externally threaded for engaging the internal threads of the body, conduits in the body for permitting the passage of liquid in the lower part of the body to enter the cap from the top 10 of the body, said container having holes in its top and bottom parts for supporting the syringes and other holes in the bottom for permitting liquid to enter the same.
2. A device of the class described comprising 15 a body internally and externally threaded, the body being of cylindrical shape with its lower end closed, a cap having a skirt internally threaded for engaging the external threads of the body, whereby the cap can be adjusted on the body, 20 a container externally threaded for engaging the internal threads of the body, conduits in the body for permitting the passage of liquid in the lower part of the body to enter the cap from the top 25 of the body, said container having holes in its top and bottom parts for supporting the syringes and other holes in the bottom for permitting liquid to enter the same, a disk rotatably supported on the top of the container and having holes therein of the same size as the holes in the top and bottom of the container and smaller holes 30 whereby by rotating the disk either the large holes can be placed over the large holes of the container or the small holes in the disk can be arranged over the large holes of the container.
3. A device of the class described comprising a body internally and externally threaded, the body being of cylindrical shape with its lower end closed, a cap having a skirt internally threaded for engaging the external threads of the body, 35

whereby the cap can be adjusted, a container externally threaded for engaging the internal threads of the body, conduits in the body for permitting the passage of liquid in the lower part of the body to enter the cap from the top of the body, said container having holes in its top and bottom parts for supporting the syringes and other holes in the bottom for permitting liquid to enter the same, a disk rotatably supported on the top of the container and having holes 10 therein of the same size as the holes in the top and bottom of the container and smaller holes whereby by rotating the disk either the large holes can be placed over the large holes of the container or the small holes in the disk can be arranged over the large holes of the container, a tubular member carried by the top of the container and extending into the same and having holes therein and a cap threaded on the upper 15 projecting end of the tubular member for holding the disk in place and for holding articles in the tubular member.

4. A device of the class described comprising a body internally and externally threaded, the body being of cylindrical shape with its lower 20 end closed, a cap having a skirt internally threaded for engaging the external threads of the body, whereby the cap can be adjusted, a container externally threaded for engaging the internal threads of the body, conduits in the body for permitting the passage of liquid in the lower part of the body to enter the cap from the top 25 of the body, said container having holes in its top and bottom parts for engaging the syringes and other holes in the bottom for permitting liquid to enter the same, a ring threaded to the exterior part of the body and having a gasket thereon for engaging the lower end of the cap. 30
